UNITED STATES PATENT OFFICE.

ALFRED N. BOWMAN, OF OXFORD, OHIO.

POWER HAMMER.

Application filed September 29, 1927. Serial No. 222,832.

This invention relates to a power hammer.

It is primarily aimed to provide an apparatus of this kind having an improved frame consisting of novel coating parts of steel so associated as to greatly lessen the weight of machines or frames of this general character and reduce the cost thereof practically to one-half of the present cost.

Another object is to provide a construction wherein standard shape structural steel may be utilized.

A further object is to provide an exceedingly compact construction of frame wherein the column will be located at one side of the base.

Various additional objects and advantages will become apparent from a consideration of the description following taken in connection with accompanying drawings illustrating an operative embodiment.

In said drawings:

Figure 1 is a side elevation;

Figure 2 is a side elevation taken from the side opposite to Figure 1;

Figures 3 and 4 are opposite end elevations;

Figure 5 is a top plan view;

Figure 6 is a horizontal sectional view taken on the line 6-6 of Figure 1 slightly above the oblique brace;

Figure 7 is a perspective view of the base alone.

Referring specifically to the drawings, 10 designates a base which is a channel member having its flanges 11 disposed downwardly. Bolted against the flanges 11 are angle bars 13. A column 14 of channel beam form rests on the horizontal flange of one of the bars 13 and is bolted at 15 against the vertical flange of such bar. The upper end portion of the column is inclined inwardly and upwardly at 16 to a point substantially centrally over the base 10. The 20 said column 14 is braced and rigidified by a supplemental column 17, which has a vertical portion 18 bolted to the column 14 at 19 and an oblique portion 20 whose lower end is bolted at 21 against the vertical flange of the angle bar 13 opposite to that to which the column 14 is fastened. To accommodate the attachment of the supplemental column 17, the last mentioned vertical flange is depressed or inwardly offset 30 as at 22.

Supported on the base 10 is a fabricated

pedestal or support 23 for an anvil 24. 61 The specific structure of the pedestal needs no specific description. Such pedestal is overlapped at the sides thereof by the vertical flanges of angle bars 13 which are secured thereto as by bolts 25. In addition, anchoring angle bars or plates 26 are fastened as by bolts 27 to the pedestal and as by bolts 28 to the base. 65

As usual, the hammer is vertically slideable. Such hammer is designated 27 and has a dove-tailed portion 28 slidably disposed in a vertically arranged guide bracket 29. Such guide bracket 29 is disposed at a 70 right angle to the general plane of the column 14 and it is fastened thereto by an oblique brace 30, having bolts 31 securing it to the bracket and bolts 32 securing it to the column 17 and vertical portion 18. Also an 75 angle member or plate 33 has one flange 34 bolted at 35 to the column 14 and the other flange bolted as at 36 to the bracket 29. The latter flange is vertically extended into a tongue 37 which is bolted as at 38 against 80 one of the side flanges of the inclined portion 16 of column 14. The bracket 29 is of a fabricated construction needing no specific description.

The upper end portion of the column 14 85 constitutes part of a bearing which is completed by a plate 40 bolted in place as at 41. Suitably journaled in this bearing is a drive shaft 42 having a pulley 43 thereon adapted to be driven from any suitable source of 90 power by a belt 44 trained thereover. At the other end of the shaft 42 is a disk 45 having an eccentric block 46 adjustable radially thereof and to which an outer block 47 is pivoted at 48. Adjustably fastened to 95 the outer block are a pair of vertical rods 49 carried by a clamp 50 of conventional form, which connects them to a semi-elliptic spring 51 composed of laminated leaves 52. The outer leaf of such spring 51 carries studs 100 53 which may turn in arcuate loops 44 thereof. Pins or studs 55 are adjustably connected to the pins or studs 53 by means of screws 56 and trained over the studs 55 is an endless strap 57 of leather or other flexible material and preferably of laminated construction. Such strap passes through an opening in the hammer 27 in order to suspend the latter and the strap is prevented from lateral displacement by means of washers or plates 58 carried on the studs 55. 105 The tension of the strap and spring 51 is 110

regulated through the adjustment of the screws 56.

The raising and falling of the hammer is controlled through the rotation of the eccentric drive therefor as described. A tightener for the belt 44 is shown in the form of a bell crank lever 60 pivoted at 61 to one of the side flanges of the vertical portion 18 of supplemental column 16. Such lever may have a roller 62 journaled thereon to directly engage the belt 44. Pivoted to the bell crank lever 60 is a link 64 which is pivoted to a treadle lever 66, whose fulcrum is a rod 67 extending through and journaled in the base and adjacent parts. The bell crank lever or belt tightener is normally held out of engagement with the belt since the tightener is retracted through the agency of a rod 68 pivoted to the treadle lever 66, guided for vertical movement through a bracket 69 fastened to the column 14 and having an expansive coil spring surrounding the same and engaging the bracket at one end and an enlargement 70 on the rod 68 at the other end.

Pivoted at 71 to the plate 40 is a brake lever 72 which has a brake shoe 73 pivoted thereto at 74 and adapted for coaction with an inner annular wall of the drive pulley. Such lever 72 by means of a link 75 is effectively connected to the bell crank lever 60.

The operator by depressing the treadle lever 66 controls the engagement and disengagement of the belt tightener or bell crank lever 60 with the drive belt so as to thereby control the driving of the main shaft and raising and lowering of the hammer according to the work. It will be realized that when the lever is depressed, the belt tightener engages the belt so that the latter will be tightened in order to drive the pulley of the drive shaft 43. When such treadle lever 66 is released however the belt tightener will be retracted and the belt will be loose on the pulley, thus out of driving relation with it and the brake lever 72 will be instantly applied to stop motion of the hammer since such braking means is controlled from the belt tightener.

It is to be understood that the parts con-

stituting the frame of my improved apparatus are to be made of steel and are of such construction that standard parts of steel may be utilized which aids production and minimizes the cost. At the same time the specific parts enable an exceedingly compact and relatively attenuated apparatus to be produced.

Various changes may be resorted to provided they fall within the spirit and scope of the invention.

I claim as my invention:

1. An apparatus of the class described comprising a base, columns secured to opposite sides thereof and together above the base, one of the columns having an upper portion deflected inwardly over the base, a bracket secured to the column at one side thereof, a hammer mounted by said bracket, means on the deflected portion aforesaid to operate said hammer, an anvil pedestal on said base to coact with the hammer, an angle plate secured to the bracket and to one of the columns, said angle plate having a finger secured to said deflected portion, and an oblique brace fastened to the bracket and to one of said columns.

2. An apparatus of the class described comprising a base of channel form having flanges extending downwardly, angle bars at the sides of said base with their vertical flanges extending above the base, a column of channel form secured to one of said vertical flanges, a supplemental column of channel form secured to the other vertical flange and to the first mentioned column above said base, the first mentioned column having an upper inwardly deflected portion, a pedestal on said base overlapped by said vertical flanges, a hammer to coact with the pedestal, a guide bracket for the hammer disposed at one side of the first mentioned column, an angle member secured to the first mentioned column and to said bracket, said angle member having a finger secured to the deflected portion, and operating means for the hammer journaled at the top of said deflected portion.

In testimony whereof I affix my signature.

ALFRED N. BOWMAN.
